UNITED STATES PATENT OFFICE.

CHARLES H. NORTON AND JOSEPH S. WILCOX, JR., OF WORCESTER, MASSACHUSETTS,
ASSIGNORS TO NORTON GRINDING COMPANY, OF WORCESTER, MASSACHUSETTS, A
CORPORATION OF MASSACHUSETTS.

WORK-DRIVE FOR GRINDING-MACHINES.

1,271,208

Specification of Letters Patent.

Patented July 2, 1918.

Application filed October 24, 1916. Serial No. 127,394.

To all whom it may concern:

Be it known that we, CHARLES H. NORTON and JOSEPH S. WILCOX, JR., citizens of the United States, residing at Worcester, in the 5 county of Worcester and State of Massachusetts, have invented a new and useful Work-Drive for Grinding-Machines, of which the following is a specification.

This invention relates to a work drive for 10 grinding machines of the type in which the work is continuously rotated for the production of cylindrical or conical parts, and it is the object of our invention to provide an improved work drive for machines of this 15 type.

With this object in view a principal feature of our invention consists in the provision of means for transmitting an extremely smooth and even rotative motion from a 20 member rotatable in fixed bearings to a member rotatable in a work head which is mounted on a table for reciprocation on the machine, and which may be adjusted longitudinally to any desired position on the table. 25 The axis of rotation may be fixed parallel to the ways of the table or it may be angularly adjustable within defined limits. As herein described the work is supported upon fixed or dead centers, and is rotated thereon 30 by engagement with the rotatable member. The particular manner of supporting the work is not material, however, and our invention is equally adapted for use when the work is mounted upon a rotatable support 35 with which the rotatable member is connected.

More specifically, our invention relates to the provision of positive geared connections between a drive shaft mounted in the base 40 of a machine and a rotatable work-driving member mounted upon a reciprocating work table. These geared connections in the preferred form include transmitting shafts mounted in bearings movable about horizontal axes in said base and said work head respectively, and telescoping driving connections between said shafts.

A further feature of our invention relates to the provision of means for maintaining 45 the said transmission shafts in a straight line when the work table is reciprocating and the axis of rotation of the work is parallel to the

ways of the table, and for maintaining the operating relation of said transmission shafts when the swivel table is angularly 55 adjusted for grinding conical work. Said means, in the preferred form, comprises a rod hinged to the bearing of one shaft and slidable in a sleeve hinged to the bearing of the other shaft. 60

Additional features of our invention relate to details of construction and arrangements and combinations of parts which will be hereinafter described and more particularly set forth in the appended claims. 65

Preferred forms of our invention are shown in the drawings, in which—

Figure 1 is an end elevation of a portion of a grinding machine with our improved work drive in its complete form embodied 70 therein;

Fig. 2 is a rear elevation of the parts shown in Fig. 1;

Fig. 3 is an enlarged elevation partly in section of the connections from the drive 75 shaft to the lower end of the telescoping shaft;

Fig. 4 is a horizontal sectional view taken along the line 4—4 in Fig. 3;

Fig. 5 is a vertical sectional view taken 80 along the line 5—5 in Fig. 3;

Fig. 6 is a vertical sectional view taken along the line 6—6 in Fig. 2;

Fig. 7 is a partial horizontal sectional view taken along the line 7—7 in Fig. 6; 85

Fig. 8 is a vertical sectional view taken along the line 8—8 in Fig. 7, and

Fig. 9 is a rear elevation similar to Fig. 2, but showing a modified construction.

Referring to Figs. 1 and 2 we have shown 90 portions of a grinding machine of a common type including a base 10, a work table 11 slidable longitudinally on ways 12 and 13, and a swivel table 14 mounted on the work table 11 and capable of limited angular 95 adjustment relatively thereto. A clamp 15 (Fig. 2) is provided for securing the swivel table 14 upon the work table 11, and indexes, not shown, are commonly provided to indicate the angular relation of the parts. 100 The adjustment of the table 14 upon the table 11 is commonly limited to about ten degrees each side of the zero position.

A work head 16 is mounted upon the

swivel table 14 and may be longitudinally adjusted along ways 17 and 18. A bolt 19 provides means for clamping the head to the table in the desired position. A sleeve 20 (Fig. 6) is mounted in the head 16 and a dead center 20* in the sleeve 20 supports one end of the work for engagement by the wheel W. The parts thus far described may be of the usual type and form no part of 10 our invention.

A drive shaft 21 (Fig. 4) is mounted in the lower portion of the base 10 and is connected with a source of power in any convenient manner, as by bevel gears 22 and 23.

15 The shaft 21 is herein shown as supported near one end by a ball bearing 24 mounted in a bushing 25 fitted into the side of the base 10.

A sleeve or shell 26 (Fig. 5) is pivoted to 20 swing about the axis of the shaft 21, being supported thereon by ball bearings 27 and 28 (Fig. 4). A transmitting shaft 30 (Fig. 5) is mounted in bearings 31 and 32 in the sleeve 26 and is driven from the shaft 21 by spiral gears 33 and 34 keyed to the shafts 21 and 30 respectively. The shaft 30 is thus positively driven through geared connections from the shaft 21 and is angularly adjustable about the axis of said shaft.

25 30 A work-driving rotary member, herein shown as a worm wheel 40, is mounted in the work head concentric with the sleeve 20 and is driven by a worm 41 keyed to a horizontal intermediate shaft 42 mounted above the sleeve 20 and supported by bearings 43 and 44 in the head 16. A sleeve or shell 45, (Fig. 8) similar in construction to the sleeve 26 previously described, is pivoted to swing about the axis of the shaft 42 and is supported thereon by bearings 46 and 47 (Fig. 6). A transmitting shaft 48 (Fig. 8) is carried in bearings 49 and 50 in the sleeve 45 and is connected to drive the shaft 42 through a worm 51 and a worm wheel 52 keyed respectively to the shafts 48 and 42.

35 Universal driving connections are provided between the transmitting shaft 30 mounted on the base of the machine and the transmitting shaft 48 mounted on the spindle head. These connections comprise a grooved rod 60 (Fig. 6) connected by a universal joint 61 to the lower end of the shaft 48 and a sleeve 62 (Fig. 5) connected by a universal joint 63 to the shaft 30. The 40 sleeve 62 is provided with keys 64 slideable in the grooves of the rod 60 and preventing relative angular movement of the rod and sleeve. A loose sleeve 65 is secured to the rod 60 and extends down over the member 45 62, thus protecting the movable parts from dust and dirt.

We have thus provided complete geared driving connections from the driving shaft 21 to the rotatable member 40, but some additional provision is necessary to always

5 maintain the transmitting shafts 30 and 48 in operative relation to each other.

For this purpose we provide a rod 66 having a head 67 mounted on a stud 68 extending transversely through a projection 69 formed on the sleeve 45. The rod 66 is thus mounted to swing in one direction relatively to the sleeve 45 and shaft 48, but must always swing in a plane parallel to said shaft.

75 At its lower end the shaft 66 is slideable in a sleeve 70 pivoted at 71 on a projection 72 formed on the sleeve 26. The sleeve 70 and rod 66 are thus mounted to swing in one direction relatively to the shaft 30 but must always move in a plane parallel to said shaft. The rod 66, connected as above described to both of the sleeves 26 and 45 maintains the shafts 30 and 48 in operative relation in every position of the work 80 head 16.

If the swivel adjustment of the table 14 upon the table 11 is omitted the driving connection may be somewhat simplified as 85 shown in Fig. 9. In this case the universal joints 61 and 63 may be omitted and the rod 66 and its connections will then become unnecessary. Whenever the swivel table is used, however, and whenever the shafts 30 and 48 are out of alinement in the plane of 90 Fig. 1, the universal joints and the rod 66 become necessary to maintain the shafts in 95 operative relation.

The driving connections (not shown) 100 from the rotary member 40 to the work may be of any usual construction and form no part of our invention. The method of supporting the work is likewise immaterial, the dead center herein shown being illustrative merely. Live centers or a chuck or any 105 other suitable supporting device may be substituted. It will also be evident that other changes and modifications can be made by those skilled in the art without departing from the spirit and scope of our invention as 110 set forth in the claims. Therefore we do not wish to be otherwise limited to the details herein disclosed, but what we claim is:—

1. A work drive for a grinding machine 115 having, in combination, a base, a table slideable thereon, a rotatable work support on said table, a cross shaft extending transversely of said table and connected to rotate said support, a driving shaft extending 120 transversely of said base and mounted in fixed bearings therein, said shafts being positioned in parallel horizontal planes, transmission shafts mounted in bearings movable about the axes of said first mentioned 125 shafts, and positive driving connections between the several shafts.

2. A work drive for a grinding machine 130 having, in combination, a base, a table slideable thereon, a rotatable work support on

- said table, a cross shaft extending transversely of said table and connected to rotate said support, a driving shaft extending transversely of said base and mounted in fixed bearings therein, said shafts being positioned in parallel horizontal planes, transmission shafts mounted in bearings movable about the axes of said first mentioned shafts, and positive driving connections between the several shafts including connecting elements between said transmission shafts which permit changes to be made in the distance between said shafts without interrupting their driving function.
5. A work-drive for a grinding machine, having in combination a work support, a cross shaft connected to rotate the work mounted thereon, a driving shaft, said shafts being positioned in parallel horizontal planes, transmission shafts mounted in bearings movable about the axes of said first mentioned shafts, positive driving connections between the several shafts including universal connections between the last mentioned shafts, and means to continuously maintain said shafts in operative relation.
6. A work drive for a grinding machine, having, in combination, a work support, a cross shaft connected to rotate the work mounted thereon, a drive shaft, said shafts being positioned in parallel planes, transmission shafts mounted in bearings movable about the axes of said first mentioned shafts, positive driving connections between the several shafts including universal connections between the last mentioned shafts, and means to maintain said shafts in operative relation, said means comprising a sleeve pivoted to one bearing, and a rod pivoted to the other bearing and sliding in said sleeve.
7. In a grinding machine, a base, a drive shaft supported in bearings fixed relatively to said base, a table slidable longitudinally relatively to said base, a work-head mounted on said sliding table, a work-driving member rotatably mounted in said head, and a positive geared driving connection from said shaft to said member.
8. In a grinding machine, a base, a sliding table, a work-head adjustable on said table, a work-driving member rotatable in said head, a transmitting shaft supported in a bearing angularly movable on said head and connected to drive said member, a transmitting shaft supported in a bearing angularly adjustable on said base, a driving connection between said two transmitting shafts, and means to keep said shafts in operative relation in every position of the spindle head.
9. In a grinding machine having a work-head, a work-drive comprising a shaft mounted in a bearing movable about a fixed horizontal axis, a second shaft mounted in a bearing movable about a horizontal axis in said work-head, and telescoping driving connections between said shafts.
10. In a grinding machine having a work-head, a work-drive comprising a shaft mounted in a bearing movable about a fixed horizontal axis, a second shaft mounted in a bearing movable about a horizontal axis in said work-head, and telescoping universal driving connections between said shafts.
11. In a grinding machine, a base, a table slidable thereon, a work-head adjustable on said table, a work-driving rotary member mounted in said head, a horizontal intermediate shaft mounted transversely in said head, a transmitting shaft mounted in a bearing movable about the axis of said intermediate shaft, gearing connecting said shaft and rotary member, and means to drive said transmitting shaft.
12. In a grinding machine, a base, a drive shaft supported in bearings fixed relatively to said base, a table slidable relatively to said base, a work-head mounted on said sliding table, a work-driving member rotatable in said head, and means to drive said member positively from said drive shaft, said means including a sleeve pivoted about the axis of said drive shaft, a transmitting shaft rotatable in said sleeve transversely of said drive shaft, driving connections between said shafts, a second sleeve pivoted about a horizontal axis in the work head, a second transmitting shaft rotatable in said second sleeve, telescoping driving connections between said transmitting shafts, and driving connections from said second transmitting shaft to said rotary member.
13. In a grinding machine, a base, a drive shaft supported in bearings fixed relatively to said base, a table slidable relatively to said base, a work-head mounted on said sliding table and adjustable thereon, a work-driving member rotatable in said head, and means to drive said rotary member positively from said drive shaft, said means including a sleeve pivoted about the axis of said drive shaft, a transmitting shaft rotatable in said sleeve transversely of said drive shaft, driving connections between said shafts, a second sleeve pivoted about an axis in the work head, a second transmitting shaft rotatable in said second sleeve, telescoping universal driving connections between said shaft, driving connections from said second work-driving member, and means to continuously maintain said shafts in operative relation.
14. In a grinding machine, a base, a table slidable thereon, a work-head adjustable on said table, a work-driving member mounted in said head, a horizontal intermediate shaft mounted transversely in said head above the axis of said member, a transmitting shaft mounted in a bearing movable about the axis of said member.

axis of said intermediate shaft, gearing connecting said shaft and spindle, a horizontal driving shaft mounted in said base, a transmitting shaft mounted in bearings movable about the axis of said drive shaft, gearing connecting said drive shaft and the latter transmitting shaft, a telescoping universal driving connection between said two trans-

mitting shafts, and means to maintain said transmitting shafts in operative relation in every position of the work head.

In testimony whereof we have hereunto affixed our signatures.

CHARLES H. NORTON.
JOSEPH S. WILCOX, JR.
